2 Claims. (Cl. 200—152)

The present invention relates to a liquid contact switch. More particularly, the present invention relates to a mercury-type switch that includes a rotatable capsule having separated pools of mercury for making and breaking contact in an electrical circuit.

The present application is a continuation-in-part of application Serial No. 841,381, filed September 21, 1959, and entitled "Mercury Switch," now U.S. Patent No. 3,045,088.

In the copending application, a mercury switch is disclosed that includes a unique capsule construction wherein normally separated pools of mercury are brought into contact upon rotation of the capsule to the "make" or "on" position. The present invention includes structure similar to that disclosed in the copending application and further incorporates a filler gas and a plated electrode to increase the efficiency of the switch.

In some prior known mercury contact switches, a filler gas, such as hydrogen, has been used to fill the switch capsule in order to absorb and dissipate the heat generated by the electrical arc when the circuit through the mercury pool was completed. Hydrogen was employed as the filler gas heretofore chiefly because of its high dielectric recovery rate and good thermal characteristics. However, it has been found during closing of the circuit, the hydrogen filler tends to increase the arcing between the pools of mercury. Thus even with a very clean hydrogen filled capsule, the high recovery rate of the hydrogen increases the arc energy between the mercury pools, and multiple interruptions will occur on "make" of the switch. These interruptions result from the explosive reaction that takes place between two spherical surfaces of mercury in a hydrogen atmosphere, and the initial high in-rush current under such conditions tends to vaporize the mercury and thus separates the circuit which results in an arc. The specific heat characteristics and high thermal conductivity of hydrogen permits a rapid reestablishment of contact conditions, and the cycle is repeated until an interruption occurs at a sufficiently low voltage that the resulting current is not effective in initiating vaporization. As a result of the interruptions or explosions, deposits form which tend to cause more and violent interruptions during "make" of the circuit and thereby decrease the efficiency of the switch.

It has been further discovered that the use of hydrogen as the gas filler in a mercury switch capsule increases the switch resistance in that the constant vaporization of the mercury at high temperatures and under pressures greater than atmosphere gradually caused an amalgam of mercury and hydrogen to form. This amalgam gradually increased in hydrogen content and eventually resulted in sluggishness of the mercury. As the mercury increased in sluggishness, the operating angle of the capsule at which the switch established contact also increased and eventually resulted in a breakdown of the switch.

The present invention completely eliminates the use of hydrogen as the filler gas in the mercury capsule and employs as the filler gas an inert gas such as argon. Argon, when utilized as the sole gas filler, has been found to eliminate the breakdowns in the switch oc-

2

casioned by the use of hydrogen since the thermal characteristics thereof provide a reestablishment of the circuit more slowly than in the case of hydrogen. Moreover, since argon is inert, it will not form a compound with either the electrodes, mercury or the casing of the capsule even when the switch is subjected to severe operating conditions.

The mercury switch embodied herein further defines an improvement over the prior known mercury switches in that it includes a nickel plated electrode that extends into the mercury pool within the switch capsule. By nickel plating the electrode, an active electrode surface is produced which is easily wetted by the mercury thereby assuring a clean mercury to mercury contact. Since nickel in itself is only very slightly soluble in mercury, an offensive amalgam will not be formed.

It is, therefore, an object of the present invention to provide an electric switch utilizing a liquid contact circuit controller.

Another object of the present invention is to provide an electric mercury switch which includes a capsule having a well member positioned therein for creating a mercury-to-mercury make or break action.

Still another object of the present invention is to provide a mercury electric switch which is positive in action and which includes a unique form of an electrode or contact member that cooperates with the well member within the capsule to close the circuit between the electrical contacts of the switch.

Still another object of the invention is to provide a mercury switch having a capsule formed with an electrode extending outwardly therefrom for making electrical contact with a contact member.

Still another object is to provide a mercury switch that includes a capsule filled with an inert gas and operating with a mercury-to-mercury make or break action.

Still another object is to provide an electric switch utilizing a liquid contact circuit controller that includes a capsule filled with an inert gas such as argon.

Still another object is to provide a mercury switch including a capsule filled with two separate pools of mercury, the pools uniting on "make" and separating on "break," and further including a nickel plated electrode that extends into one of the mercury pools.

Still another object is to provide an electrode for use in a mercury switch that is nickel plated, thereby enabling better wetting of the electrode with mercury, which in turn assures a clean mercury to mercury contact during operation of the switch.

Other objects, features and advantages of the invention will become apparent as the description thereof proceeds when considered in connection with the accompanying illustrative drawings.

In the drawings which illustrate the best mode presently contemplated for carrying out the present invention:

FIG. 1 is a front elevational view of the electrical switch embodied in the present invention;

FIG. 2 is a sectional view of the electric switch taken along lines 2—2 in FIG. 1 and illustrating the "on" position of the switch;

FIG. 3 is a sectional view similar to FIG. 2, illustrating the switch in the "off" position;

FIG. 4 is an enlarged view of the operating button and capsule assembly showing the mercury-to-mercury contact within the capsule well when the switch is disposed in the "on" position;

FIG. 5 is an enlarged view of the operating button and capsule assembly similar to FIG. 4, showing the location of the mercury within the capsule when the switch is disposed in the "off" position thereof;

FIG. 6 is a sectional view taken along line 6—6 of FIG. 4; and

FIG. 7 is a sectional view taken along lines 7—7 in FIG. 6.

Referring now to the drawing, FIGS. 1 through 3, the mercury switch embodied herein is generally indicated at 10 and includes a mounting strap 12 having openings 14 formed at opposite ends thereof, the openings 14 being adapted to receive a screw or other fastening element (not shown) for mounting the strap in position in a recess formed in a wall or the like. The mounting strap 12 further includes a rectangularly shaped opening 16 formed centrally thereof which is adapted to receive therethrough the operating button of the switch. Formed on the marginal portions defining the opening 16 are arcuate shaped portions 17 that provide for the movement of the operating button as will be described hereinafter.

Secured to the mounting strap 12 by screws 18 which extend through suitable openings formed in the mounting strap is a body member 20, the rearmost portion of which projects into the recess of the wall fixture on which the switch 10 is mounted. As shown in FIG. 2, the body 20 member 20 is formed in a shell construction, preferably of molded plastic, and includes oppositely positioned outwardly extending recessed ears 22 and 24 (FIG. 1). Formed in each of the ears 22, 24 is a recess 25 that receives a terminal screw 26 therein. The terminal screw 26 threadedly extends through an opening formed in a contact head 28, the contact head 28 being formed integral with a longitudinally extending contact member 30. A contact member 32 (FIG. 6) is formed similarly to contact member 30 and includes a contact head that receives a terminal screw that in turn extends into a recess formed in the ear 24. It will be understood that contacts 30 and 32 are of identical construction except that they are reversely disposed and extend adjacent opposite sides of body 20 so that their respective contact heads can engage ears 22 and 24 in the manner indicated.

As shown in FIGS. 2 and 6, the contact members 30, 32 extend substantially the length of the interior of the body member 20 and are in spaced parallel relation with respect to each other. Enlarged central portions 33 of the contact members are dished to define bearing surfaces for rotatably receiving a capsule generally indicated at 34. The capsule 34, which defines the liquid contact circuit controller of the subject invention, is formed in a generally tear-drop shape, as seen in cross section in FIGS. 2 and 4, and includes a metallic cap 36 formed with a peripheral flange 38 (FIG. 6). Joined to the flange 38 as by welding or the like and enclosing the cap 36 is a plate 40 having a central opening 42 formed therein. A seal 44 is positioned within the opening 42 and is adapted to rigidly receive therethrough, in sealing relation therewith, an arm of an electrode to be described hereinafter.

Located within the capsule 34 and positioned at the narrow portion of the tear-drop section is a well 46. The well 46 is formed of a non-metallic, non-corrosive material, such as ceramic, and includes a chamber 48 in which a small pool of mercury 50 is disposed. The chamber 48 is defined by a rear wall 51, side walls 52 and a relatively short front wall 53 formed with an inclined upper edge. The relatively short front wall 53 prevents the small pool of mercury 50 from flowing out of the well in the "off" position of the switch, as shown in FIG. 5. The side walls 52 of the well are positioned between the rear wall of the cap 36 and plate 40 and are spaced to define the chamber 48. The well is maintained in position so that, as the capsule is rotated, the front wall 53 will either extend above or below a pool of mercury 54 disposed within the capsule but outside the well. In the "off" position of the switch, the level of the larger or major body of mercury 54 disposed within the capsule 34 extends below the upper edge of the front wall 53; thus, the body of mercury 54 is prevented from communicating with the chamber 48 of the well 46 and the small pool of mercury 50 disposed therein. As illus-

trated in FIG. 4, when the switch is moved to the "on" position, the tear-drop shaped capsule is rotated clockwise, the narrow portion of the tear drop moving downwardly to cause the well 46 to be tilted. In this position, since the surface of the body of mercury 54 remains in a horizontal or level position, the level thereof would extend above the upper edge of the wall 53, and the mercury 54 thus flows over the inclined upper edge of the front wall 53 and into the chamber 48. The mercury 54 thereby intermingles with the pool of mercury 50, and a mercury-to-mercury contact between the body of mercury 54 and the small pool of mercury 50 is effected. It is seen that the pools of mercury 50, 54 will be caused to communicate with each other with only a slight rotary movement of the capsule 34, and in practice, the large pool of mercury will flow over the wall 53 after only a slight rotation of the capsule 34. In this connection, the sharp or inclined upper edge of the front wall 53 provides for easier and faster "makes" and "breaks" of the switch circuit. It has been found that in order to insure "make" or "break" with this relatively slight rotary movement of the capsule, the ratio by volume of mercury 54 to pool 50 should be greater than one to one.

In order to rotate the capsule 34, the capsule is formed with an outwardly dished portion 56 on the bottom wall of the cup member 36, the outwardly dished portion 56 making bearing contact with the corresponding dished portion 33 of the contact element 32. An electrode 58 is disposed within the chamber 48 of the well 46, being spaced from the side walls 52 and extending upwardly therefrom. The chamber 48 is proportioned to easily accommodate the electrode 58 wherein the mercury can more freely flow into the chamber 48 during the "make" operation. The outer end of the electrode 58 is formed with an arm 60 that is joined to the portion that extends within the well 46 at right angles with respect thereto, and another arm 62 of the electrode is joined to the arm 60 at right angles thereto, extending through the seal 44. The arm 62 has a contact button 64 secured to the end thereof which is formed with a convex outer face that cooperates with the dished portion 33 of the contact member 30. As illustrated in FIG. 6, the dished portion 56 and the contact button 64 mount the capsule 34 for rotation between the contact members 30 and 32. It will be understood that the securing of flange 38 to plate 40 effects an air-tight seal therebetween, while at the same time the seal 44 is air tight, whereby the capsule is effectively hermetically sealed. This, of course, is important in mercury switches of this type in order to prevent undesirable oxidation of the mercury and electrode.

The capsule 34 is adapted to be rotated in the body member 20 by an operating button generally indicated at 70, the operating button 70 including a handle portion 72 to which an arcuate shaped body 74 is integrally joined. The underside of the body 74 is formed with arcuate surfaces 76, 78 (FIG. 6) which are spaced apart to define an arcuate shaped groove 80 therebetween, the groove 80 receiving the flange 38 of the capsule 34 and the plate 40 therein. Joined to the sides of the body 74 extending outwardly therefrom and following the arcuate configuration thereof are flanges 84, one of which is shown in FIGS. 2 and 4. Formed on the flanges 84 are projections 86 which, as shown in FIG. 2, in the assembled position of the switch are positioned within the arcuate portions 17 of the strap 12 and cooperate therewith to provide a frictional force for stabilizing and maintaining the button in a selected position. The operating button 70 is adapted to positively engage the capsule 34 for imparting rotating movement thereto by means of a projection 88 formed on the underside of the arcuate surface 76. The projection 88 extends into a recess 90 formed in the wall of the cap 36 and, as seen in FIGS. 2 and 5, is held in snug engagement therein by the frictional pressure between the projections 86 and the arcuate portions 17 of the strap 12. It is seen that rotation of the operat-

ing button 70 will cause the capsule member 34 to rotate therewith, the limit of movement being predetermined by the movement of the handle portion 72 of the operating button 70 within the switch cover plate (not shown).

In mercury switches of the type embodied herein, it is important to establish immediate contact between the mercury and the electrode when the capsule is rotated to the "on" or "make" position. In some of the prior known mercury switches, a gas filler, such as hydrogen, was introduced into the capsule for the purpose of absorbing and dissipating heat that resulted when the electrical circuit was established between the mercury and electrode. It has been found that the use of a hydrogen filler prevented instantaneous making between the mercury pool and the electrode and that, moreover, multiple interruptions occurred on making contact, even with a very clean hydrogen-filled switch. This latter phenomenon is due to the explosive reaction that takes place when point contact is made between two spherical surfaces of mercury in a hydrogen atmosphere and when such surfaces are part of an electrical conducting circuit. In order to eliminate the undesirable sparking resulting from use of a hydrogen atmosphere, an inert gas such as argon is employed as the gas filler in the present invention and is introduced under pressure into the capsule 34. Argon, when utilized as the sole gas filler, increases the efficiency of the switch since in addition to its inertness, it has a relatively low capacity to conduct heat, thus resulting in lessening of the explosive effect of the individual contacts. Argon also tends to prevent reestablishment of a high voltage contact, thereby preventing interruptions when the capsule is moved to the "make" position, and, furthermore, argon even under high temperature conditions is not capable of forming an amalgam or a compound with the mercury or electrode. As employed in the present invention, the argon filler is introduced into the capsule in pure form and is maintained at a pressure not below one atmosphere. Under operating conditions, it has been found that excellent results are produced by maintaining the pure argon in the capsule at thirty p.s.i.

Argon used above as a filler gas is also beneficial in the interruption of the electrical circuit in the switch. With an argon atmosphere contained in the switch capsule as the sole gas filler, ionization of the mercury vapor is largely avoided, the argon acting to contaminate the mercury vapor atmosphere on the occasions when it is copiously formed. In addition to this, when a high voltage is available, an argon glow discharge forms which has a low current carrying capacity yet serves as a shunt resistance to limit the potential available for initiating an arc.

Observation of the "make" and "break" events of the switch embodied herein have been made by use of a cathode ray oscilloscope, and in this study the oscilloscope input was connected directly across the switch contact so that with the switch open a trace of line voltage was observed, and with the switch closed a zero voltage horizontal trace was made.

The "make" event has three trace forms. If the circuit is completed on a rising voltage but before the potential is great enough to start the mercury vaporization, no instantaneous "break" follows, and the current is immediately established. The same is true if the initial contact is in a falling voltage below the critical value. If, however, the contact is made at any time above the critical voltage, the circuit is immediately interrupted and the argon glow is formed. This persists until the voltage falls to zero and the circuit is permanently established.

The "break" events are of a similar character except that the factor of contact separation is introduced. If slow separation of contacts takes place, the traces on the oscilloscope are identical with the three conditions described above for "make." Where the circuit is opened at low voltage, either rising or falling, an immediate and permanent interruption occurs. If the circuit is opened

at a time when enough potential is available to start the argon glow, the glow will be continuous until the next zero voltage is reached to accomplish permanent interruption. However, if the separation of the contacts takes place rapidly enough, a point is reached where the opening may be enough to permit activation of the mercury. If the potential at this instant is also sufficient, a mercury arc can be formed which is extinguished as the voltage passes through zero.

In contrast to the argon filler, a hydrogen filler, such as utilized in the prior known switch constructions, causes rapid multiple interruptions of the switch circuit, with reestablishing occurring many times during the half cycle voltage period. As indicated on the oscilloscope, the multiple interruptions produce a plurality of saw-tooth traces, each saw-tooth representing an explosion of mercury that is quickly cooled by the presence of hydrogen.

As has hereinbefore been pointed out, the electrode 58 is coated with a nickel plating 92 that results in better wettability of the electrode, thereby assuring a clean mercury-to-mercury contact. It should be noted, however, that in the normal manufacture of the switch 10, it is necessary to pass the plated electrode together with the glass 44 and plate or header 40 through the furnace in which the seal between these parts is being effected. Since this furnace pass would normally destroy the active nickel surface, it is important that the furnace treatment atmosphere be strongly reducing, such as by introducing a quantity of hydrogen, since a reducing atmosphere will not destroy the active nickel surface. It has been found, however, that upon exposure to air the nickel plating is even more susceptible than usual to oxidizing in view of this treatment in a reducing atmosphere, and hence it is essential that the cap 36 be assembled to the plate 40 as quickly as possible after the furnace sealing operation.

It will be understood that the better wettability of electrode 58 that results from nickel plating 92 enables contact to be made with a minimum throw of the switch. In practice, it has been found that with an unplated electrode, the throw of the switch must be increased by as much as 4° to 5° before contact is made. This is due to the fact that the absence of plating 92 results in an electrode that has a tendency to resist wetting by the mercury, thus failing to achieve the clean mercury-to-mercury contact which enables the switch to "make" more quickly.

It is also of importance to note that the corner 94 of side wall 52 which abuts plate 40 overlaps and bears against a small portion of glass seal 44 (FIGS. 4-6). This is important in that when the plate 40, seal 44, well 46 and electrode 58 are passed through the furnace to effect the seal between plate 40, seal 44 and electrode 58, the overlapping corner 94 of well 46 will automatically fuse to glass seal 44 thereby holding the well 46 firmly in position, both during subsequent assembly of cap 36 and operation of the completed switch.

In operation, when the mercury switch is located in the "off" position, as seen in FIG. 5, the handle portion 72 of the operating button 70 is pointing downwardly. In this position, the small pool of mercury 50 is prevented from making contact with the larger body of mercury 54 by the barrier defined by the shortened wall 53 formed on the front of the well 46. When the handle portion 72 is moved upwardly to the position shown in FIG. 4, the larger body of mercury 54 is caused to flow over the wall 53 and into communication with the interior of the well 46, thereby making contact with the small pool of mercury 50. Electrical contact is thereby established through the contact member 30, electrode 58, mercury bodies 50, 54, the cap 36 and the contact member 32. The inclined or pointed upper edge of wall 53 facilitates the "make" and "break" action of the switch during rotation thereof.

It is seen that the present invention provides a mercury switch that is simple in construction, effective in operation, and inexpensive to manufacture. The mercury-to-mer-

cury "make" and "break" operation insures a longer life of the switch and provides for rapid make and break between the contact elements. The argon filler eliminates the interruptions normally associated with gas fillers and tends to prevent oxidation, flaking and formation of undesirable compounds within the capsule. The plating on the electrode within the capsule cooperates with the argon filler to produce an active electrode surface that results in a decrease of the throw angle of the switch and that generally increases the efficiency thereof.

It will be obvious to those skilled in the art that various changes may be made without departing from the spirit of the invention, and therefore the invention is not limited to what is shown in the drawings and described in the specifications, but only as indicated in the appended claims.

What is claimed is:

1. In an electric switch, a liquid contact circuit controller comprising a hermetically sealed capsule constructed of conductive material, a well formed of non-conductive material positioned within said capsule, a main body of conductive liquid located within said capsule adjacent to but outside of said well, a secondary body of conductive

liquid located within said well, an electrode extending into said well into contact with said secondary body and having a further portion extending outwardly through said capsule, and means insulating said electrode from said capsule, said insulating means comprising a glass seal in the wall of said capsule through which said electrode extends whereby no contact is made between the electrode and the conductive capsule wall, said well having a portion in engagement with said glass seal and bonded thereto so as to maintain said well fixedly positioned within said capsule.

2. The switch of claim 1 further characterized in that said well is ceramic, the portion of said well which is in engagement with said glass seal being fused thereto in order to effect the aforesaid bond therebetween.
